UNITED STATES PATENT OFFICE.

GEORGE RUDISCHHAUSER, OF NEW YORK, N. Y.

RADIATOR-AIR-VALVE PROTECTOR.

1,267,275.

Specification of Letters Patent. Patented May 21, 1918.

Application filed January 26, 1918. Serial No. 213,971.

To all whom it may concern:

Be it known that I, GEORGE RUDISCHHAUSER, a citizen of the United States, and a resident of the city of New York, (borough of Manhattan, in the county and State of New York, have invented a new and Improved Radiator - Air - Valve Protector, of which the following is a full, clear, and exact description.

10 My invention relates to means for preventing unauthorized persons from manipulating the air valve of a radiator and thereby interfering with the proper working of the heating system.

15 An object of the invention is to provide a simple and inexpensive contrivance which can be easily applied to a radiator air valve.

Another object of the invention is to provide a contrivance of the class described 20 which is applicable to a radiator air valve which has a top or bottom vent or both.

With the above and other objects in view, the nature of which will more fully appear as the description proceeds, the invention 25 consists in the novel construction, combination and arrangement of parts as herein fully described, illustrated and claimed.

In the accompanying drawings, forming 30 part of the application, similar characters of reference indicate corresponding parts in all the views.

Figure 1 is an elevation of a radiator air valve having a top air vent and which is provided with a protector embodying my invention, the protector being shown in vertical section;

Fig. 2, an elevation of an air valve having a bottom and top vent provided with a protector, shown in vertical cross section, 40 and which protector prevents access to either vent of the valve; and

Fig. 3, an elevation of the protector as it would appear if a section were taken on line 3—3, Fig. 2.

45 Referring to Fig. 1, 4 is a suitable tubular shell of a diameter sufficiently large to receive therein a radiator air valve 5. Preferably the diameter of the tubular shell is large enough to accommodate the widest 50 part of the valve, but this is not necessary. It may be made large enough to engage the part of the valve directly below the vent 6, particularly in cases where the valve has only a top vent as shown in Fig. 1. The 55 shell is sufficiently long to present a material clearance above the vent 6. It has at

the top holes 7 which are the vents of the shell and allow the proper operation of the radiator air valve.

The shell is retained on the radiator air 60 valve 5 by means of a set screw 8, for which the shell 4 has a transverse socket 9 extending transversely of the shell near the upper part of same. The shell has openings registering with the socket, one opening 10 being of a diameter equal to that of the socket, while the other opening 11 is smaller so that the side of the shell presents a shoulder for the collar 12 of the set screw. The head 13 of the screw is preferably of angular 65 cross section so that a special socket wrench is necessary for manipulating said screw within the socket. The screw has a threaded opening in the radiator body 14 whereby the shell can be secured to the radiator. A suitable spacer 15 is provided between the shell 20 and the radiator to maintain the shell in proper alinement with the radiator valve 5.

When the air valve 5' (see Fig. 2) has a top and bottom vent 6' then, in addition to 80 the shell 4, a cover shell 16 is provided which is similar to the shell 4 but slightly larger so that it may telescope over the shell 4 (see Fig. 3). Since the cover shell must clear the stem 17 of the air valve, it is provided with a longitudinal slot 18 which is open at the open end of the cover shell 16. In view of the fact that the stud securing the shells to the radiator body must be in vertical alinement with the stem 17, the slot 85 18 is deviated from the vertical to provide a body portion outside the opening for the set screw in the cover shell 16, thereby the set screw will lock the cover shell while it locks the shell 4 and thereby prevent the 90 removal of either by an unauthorized person. It is self-evident that the cover shell has an opening 19 which registers with the opening 10 to give access to a socket wrench to 95 manipulate the set screw.

100 From the above description it will be seen that a radiator air valve equipped with a protector as described will prevent any unauthorized person from manipulating the valve of the vent 6 and thereby interfere 105 with the proper operation of the heating system. It will also prevent an unauthorized person from detaching the radiator air valve.

I claim:

110 1. In a protector for radiator air valves, a tubular shell having an open end adapted

- to admit the air valve so that the air vent of the air valve is located within the shell, a socket disposed transversely of said shell, and a set screw having an annular head 5 adapted to be located within the socket, said screw being adapted to secure the shell to a radiator when the shell is engaging the radiator air valve, said shell having openings constituting vents.
- 10 2. In a protector for radiator air valves, a tubular shell having an open end for receiving a radiator air valve, a similar tubular shell adapted to telescope over the first, a transverse socket in the first shell, and a 15 set screw having an annular head adapted to be located within the socket, said screw being adapted to engage the two shells and secure the same to a radiator when said shells inclose a radiator air valve.
- 15 3. In a protector for radiator air valves, a tubular shell having an open end adapted to admit a radiator air valve, a socket disposed transversely of said shell, said shell having openings registering with said socket,
- one of said openings being of a smaller diameter than the socket to form an abutment for a set screw, and a set screw having an annular head adapted to be located in said socket when securing the shell to the radiator to protect the valve.
- 20 4. In a protector for radiator air valves, a tubular shell having an open end adapted to admit a radiator air valve, a transverse socket in said shell, said shell having openings in register with the socket, one of said openings being of a smaller diameter than the socket, a cover shell adapted to telescope over the first and having a longitudinal slot to clear a portion of the air valve, said cover shell having openings adapted to register with the socket, and a set screw having an annular head adapted to be disposed within the socket and project through the smaller opening of the first mentioned shell by means of said screw, said shells being adapted to be secured to the radiator about the air valve.

GEORGE RUDISCHHAUSER.
